UNITED STATES PATENT OFFICE.

CHARLES Y. KNIGHT, OF CHICAGO, ILLINOIS.

EXPLOSION-ENGINE.

1,072,860.

Specification of Letters Patent.

Patented Sept. 9, 1913.

Application filed February 4, 1910. Serial No. 542,100.

To all whom it may concern:

Be it known that I, CHARLES Y. KNIGHT, a citizen of the United States, residing at Chicago, in the county of Cook and State 5 of Illinois, have invented certain new and useful Improvements in Explosion-Engines, of which the following is a full, clear, and exact specification.

This invention relates to explosion engines 10 in which the power is generated within the cylinder directly against the piston by an explosion, and it is designed as an improvement upon that type of explosion engine in which the cylinder moves with relation to a 15 fixed abutment or head therein, and also with relation to the piston for controlling or partially controlling communication with the cylinder, the cylinder being guided by a sliding sleeve valve which reciprocates in a 20 casing and coöperates therewith also for controlling communication with the cylinder. In engines of this type this sleeve valve which incloses the cylinder is necessarily thin in order that the heat from the reciprocating 25 cylinder may be radiated with sufficient rapidity to prevent overheating, and the construction is such that the sleeve valve moves at one time in a direction contrary to the movement of the cylinder or else is 30 substantially at rest during the motion of the cylinder, and hence is liable to be cramped or seized between the casing wall and the cylinder by the lateral thrust of the piston, due to the pressure of the explosion 35 while the piston rod is disposed at an oblique angle with relation to the axis of the piston, thus resulting in unnecessary strain upon the sleeve valve and upon the eccentricities or other connections for operating it.

40 The present invention is designed to overcome these possible defects and has for one of its objects to provide the reciprocating cylinder with a fixed guide to slide in and to relieve the slide valve, which coöperates 45 with the casing for controlling communication with the cylinder, from any strain or pressure due to the aforesaid lateral thrust of the piston during the working stroke.

50 The inwardly projecting fixed head in engines of this type has heretofore made it necessary to cup the head in order to provide adequate combustion space or clearance, and this construction and formation results in having the igniter or spark plug situated at 55 the apex of the dome of this combustion space in the head and consequently at a

point where the gas is liable to be foul or more or less contaminated by the remaining products of the previous explosion.

The present invention is designed to overcome this objection, and has for another object to so construct and arrange the parts that the fresh incoming gas will be discharged into the combustion space of the head contiguous to the igniter or spark plug, 60 whereby the vicinity of the plug will not only be occupied by a fresh explosive mixture but the plug itself will be cooled by the incoming charge.

In engines of the aforesaid type, the outer 70 sleeve valve is subject to expansion due to the radiated heat of the cylinder which, of course, also expands, and consequently, unless proper clearance between the sleeve and the cylinder and between the casing and 75 the sleeve valve be provided, there is a possibility of the sleeve valve being seized either by the cylinder or by the casing, and even though such seizure may not be sufficient to damage the parts, it subjects the mechanism 80 to an unnecessary strain and detracts from the power of the engine.

The present invention is designed to obviate the possibility of these results, and has for another object to so construct and 85 arrange the outside slide valve which reciprocates with relation to the cylinder, that it will not be materially affected by any expansion due to heat radiated from the cylinder or by the expansion of the cylinder, and 90 consequently may be composed of steel instead of cast iron so as to be stronger and more durable than heretofore, it being understood that with the sleeve valve form of slide valve heretofore employed it was 95 highly important that both the cylinder and the sleeve valve be composed of cast iron or other suitable metals having substantially the same coefficient of expansion.

With a view to the attainment of these 100 ends and the accomplishment of certain other objects which will hereinafter appear, the invention consists in the features of novelty shown in the accompanying drawings, described in the specification, 105 and particularly pointed out in the claims.

In the said drawings, Figure 1 is a vertical or longitudinal section of an explosion engine showing an example of this invention. Fig. 2 is a detail perspective view of 110 the slide valve and the cylinder casing filling. Fig. 3 is a cross-section of the engine

taken on the line 3—3, Fig. 1. Figs. 4 to 7, inclusive, are sectional and diagrammatic views illustrating the positions of the port-controlling elements during the four periods 5 of the cycle of a four-cycle engine, Fig. 4 being an illustration of the parts in the position they assume at or about the commencement of the suction stroke; Fig. 5 the position they assume at or about the commencement of the compression stroke; Fig. 6 the position they assume at or about the commencement of the explosion stroke, and Fig. 7 the position they assume at or about the commencement of the exhausting stroke. 15 And Fig. 8 is a cross-section of a cylinder casing embodying a modification hereinafter described.

1 is the main body of the cylinder casing which may be fixed against movement in 20 any suitable way, as by means of a base or crank case 2, upon which it is mounted and in which the usual crank shaft 3 and crank 4 are journaled in the ordinary way, this cylinder casing being, if desired, provided 25 with a water jacket 5, for cooling purposes, as will be understood. Arranged axially within the cylinder casing is a reciprocating cylinder 6, in which the piston 7 works and reciprocates with relation thereto, the piston 30 ton being connected to the crank 4 in any suitable way, as by a piston rod 8. Fixed within one end of the reciprocating cylinder 6 is a head 9, which completely closes that end thereof and is rigidly held against movement therewith and with the piston in any 35 suitable way, as by being mounted upon and closing the end of the cylinder casing 1. This head is dome-shaped at its inner end, as before mentioned, for the purpose of providing sufficient clearance or combustion 40 space, and at the top of the dome is introduced a suitable igniter or spark plug 10, or any other means may be provided for igniting the charge introduced into the cylinder 45 6 directly between the head and the piston.

The cylinder casing 1 is provided with intake and exhaust ports 11, 12, and if desired these may be situated on the same side of the casing, one in advance of the other 50 lengthwise of the axis of the casing, and the cylinder 6 at the same side is provided with an exhaust port 13 adapted to communicate with the exhaust port 12. The cylinder 6 is also provided with an intake port 14 respectively moved from the port 13 in the length of the cylinder and which port 14 is adapted to communicate with the intake port 11, but it will be seen that the mere aperture constituting the port 14 is of but little consequence, as the active portion of the cylinder 6 is that portion of its wall which lies between the two ports 13 and 14, and serves to close or to cover the intake port 11 at certain periods, all of the wall of the cylinder 6 beyond or above the intake port 14,

therefore, being of no consequence so far as the control of the intake port 11 is concerned or so far as concerns the control of communication with the interior of the cylinder 6; but in practice it is of course desirable to have some form of extension above the lower edge of the port 14 to hold the packing rings of the head in place when cylinder 6 descends or moves outwardly, and the form shown in the drawing is therefore adopted as a convenient means of accomplishing this end. Coöperating with the casing 1 for controlling the ports 11 and 12 is a slide valve 15. This also has intake and exhaust ports 16, 17 formed therein and adapted to alternately register with the intake and exhaust ports 11, 12, respectively, as the slide valve is reciprocated, thereby at one time permitting of communication between the interior of the cylinder 6 and the ports 11, 12, and at other times shutting off such communication, but the controlling portion of this slide valve is that portion which lies between the two ports 16 and 17, and hence ports as mere apertures in the slide valve 15 are not essential, it being apparent that the wall of the slide valve might be omitted from the adjacent sides of the two ports 16, 17, outwardly an indefinite extent without affecting the efficiency of the slide valve to close the ports 11 and 12, but the continuous form of slide valve having the ports 16 and 17 cut therein as shown, is preferable for the sake of strength and to provide a better guiding wall for the cylinder 6, as well as a means of connection between the slide valve and its operating mechanism, as will be presently explained. The head 9 is also provided with an intake port 18, which is arranged to communicate with the intake port 11 and whose inner end discharges at a point adjacent the igniter or spark plug 10 high up into the dome of the head so that the dome will not only be provided with fresh explosive mixture, but the plug will be cooled by the incoming charge. At both sides of the intake port 18, or above and below the same, are situated packing members 19, 20, which may be in the form of piston rings, but both of these are of sufficient width to 115 respectively cover the ports 13 and 14 in the cylinder during the compression and working or explosion strokes, whereby the interior of the cylinder 6 will be hermetically sealed without possibility of leakage 120 during both of these high-pressure periods.

The interior of the cylinder casing is preferably cylindrical and concentric with the cylinder 6, but its circumference is formed on different radii in the same transverse plane, so that the interior will be of a larger diameter throughout its length on one side than it is on the other side. The cylinder 6 fits immediately contiguous to the face of the casing 1 along the side of its smaller diameter 133

ter and which side forms a stationary guide for the reciprocating cylinder. The slide valve 15 is interposed directly between the cylinder 6 and the casing 1 at the opposite side or place where the cylinder casing is of enlarged diameter. Consequently there is formed in the cylinder casing two parallel guide-ways 21, 21', which are situated where the small diameter leaves off and the larger 10 diameter commences, and between these guide-ways is situated the slide valve 15, which is arc-shaped and conforms to the outer circumference of the cylinder 6 as well as to the inner circumference or face of the 15 casing 1. The slide valve may, if desired, be coterminous in length with the casing and connected at one end to suitable operating means, but it is preferably slightly longer than the casing, as shown in Fig. 1, and projects 20 into the crank case where it is provided with a lug 22 affording means of attachment to the mechanism for operating it, as will be presently explained. As a convenient and efficient method of thus constructing the 25 casing 1 with an internal diameter formed on different radii, as before explained, the casing may first be bored perfectly cylindrical in the ordinary way, and a separate cylinder may then be formed and split 30 lengthwise along the lines of the shoulders or guideways 21, 21', to produce on the one hand a filling to fill the space between the reciprocating cylinder 6 and the integral wall of the casing, and produce on the other 35 hand the slide valve 15, which will be of the same thickness as the remaining portion of the cylinder from which it is cut, and will of course be formed upon the same arc. These two elements, namely, the filling 23 40 and the slide valve 15, when placed together in the casing 1, around the cylinder 6, will accurately center the cylinder and form adequate guiding means therefor, while the longitudinal edges of the filling member 23 45 will serve to guide the valve 15. The filling 23, however, must be held against longitudinal movement in the casing, and this may be accomplished in any suitable way as, for example, by providing the filling 23 with a 50 flange 24 which may be turned on the element 23 when the cylinder composing the two parts 15 and 23 is made, and afterward removed from the part 15. This flange 24 is received in a circumferential groove in 55 the inner face of the casing 1, as shown in Fig. 1, and holds the filling 23 against longitudinal movement while both the filling and the valve 15 are held against possible lateral motion by the reciprocating cylinder 6. The 60 fixed guiding portion 23 of the casing 1 is situated on that side of the casing which receives the lateral thrust of the reciprocating cylinder 6, due to the tendency of the piston to move laterally when the piston rod 65 assumes an oblique-angle with relation to

the axis of the piston during the working or explosion stroke, so that this pressure will be borne by the fixed part of the casing and none of it will be received by the slide valve 15.

The reciprocating cylinder 6 and slide valve 15 may be reciprocated relatively to one another and to the piston and head by any suitable means for causing them to open and close the ports which they control according to the cycle of the engine in which they are employed, but it will of course be understood that a mechanism of this character will be of no especial advantage in any cycle excepting that which comprises a plurality of inward piston strokes to each working or explosion stroke. In the present example the engine is by preference a four-cycle type, and the movements complementary to this type may be conveniently produced by a pair of eccentrics 25, 26, whose eccentric straps 27 and 28 are connected respectively by connecting rods 29 and 30 with the lug 22 on the slide valve 15, and a similar lug 31 on the reciprocating cylinder 6. These eccentrics are set one in advance of the other for this cycle, the eccentric 26 of the cylinder being set approximately 90 degrees in the lead of the eccentric of the slide valve. These eccentrics are mounted upon a suitable shaft geared to the crank-shaft 3, or otherwise operatively connected with the piston in the ratio of two to one by means of a sprocket chain 32 and sprocket wheels 33, 34, or other suitable gearing.

In the modification shown in Fig. 8, the differential radii of the inner diameter of cylinder casing 1 is produced by counter boring, so that a separate filling such as element 23, is avoided and the water space may be brought closer to the wall of the reciprocating cylinder. Any suitable method may be followed for accomplishing this such, for example, as first boring two halves of two cylinders secured together to produce the larger diameter, then boring two halves of two cylinders on the smaller diameter, and finally exchanging the halves.

Referring to the diagrammatic illustrations of the movement of the port-controlling elements contained in Figs. 4 to 7 inclusive, let it be supposed that the suction stroke is about to commence as in Fig. 4. At this period the main crank 4 is in about the position illustrated in the lower orbit of Diagram A, and is about to start downward with the piston, while the eccentrics 25 and 26 of the cylinder 6 and slide valve 15, respectively, are in substantially the positions of the black spot 26 and the light spot 25 or circle 25 in the upper orbits of Diagram A, and the ports 13 and 14 of the cylinder 6 are in their middle or intermediate position, while the ports 16 and 17 of the slide valve are at substantially the lower extremity of

100

105

110

115

120

4

their descending stroke. These ports assume, during each cycle of the engine, three main important positions, which are represented by or correspond with the extreme 5 upper position, the quarter throw and the extreme lower position or half throw of the eccentrics, and these three main positions of said ports are indicated approximately in these diagrams by the two parallel rows of 10 black dots ranged along the longitudinal centers of the sectioned portions illustrating the cylinder 6 and valve 15, the dots representing the points where the centers of the ports fall when the eccentrics arrive at the 15 corresponding positions in their throw. By following the course of the dark and light spots in the upper orbits of Diagrams A, B, C, and D with respect to these port centers in the various diagrams the action of the 20 port-controlling elements may be readily discerned. Adverting again to the position of the parts in Fig. 4, it will be seen that the intake port 14 of the cylinder 6 is in direct register with the intake ports 11 and 25 18 of the casing and head, respectively, and is about to register with the intake ports 16 of the valve 15. At this instant the valve port 16 is rapidly descending while the cylinder port 14 is starting to rise, but moving 30 very slowly, and consequently before the piston has traveled a material portion of its downward stroke the ports 14 and 16 will be in full register with one another and with the ports 11 and 18, allowing the free in- 35 gress into the working cylinder. The exhaust port 12 of the casing at the time when the suction stroke commences is closed, however, by the slide valve 15, which descends rapidly and brings the port 17 below or 40 into a lapped position with the wall of the casing, thereby preventing the charge from becoming diluted with air or spent gases sucked into the engine, even though the exhaust port 13 is open at this time. The 45 piston having descended its full stroke, bringing the slide valve down to the limit of its downward stroke and moving the exhaust port 17 to the extreme bottom center as indicated in Fig. 5 and raising the ex- 50 haust port 13 to its middle position and intake ports 14 to their middle position or centers directly opposite the rings 20 and 19, respectively, the interior of the working cylinder 6 is hermetically sealed. During 55 the next stroke or upward stroke of the piston, which is the compression stroke, these ports 13 and 14 traverse their packing rings 20 and 19 to their extreme upper positions or centers, still maintaining lapped relation to these packings. During this up- 60 ward movement of the cylinder 6 the outside slide valve rises slowly at first and then more rapidly to its intermediate position, bringing the port 17 back again to the position indicated in Fig. 4, as shown in Fig. 6.

The ignition now occurs and the explosion stroke commences, the crank being at the top of its throw. As the piston is impelled outwardly or downwardly by the explosion, the ports 13 and 14 again traverse their rings 70 20 and 19, respectively, and arrive at their middle or intermediate positions as shown in Fig. 7, when the piston is about to reach the limit of its explosion stroke, when the exhaust port 14 commences to leave its packing 75 20, thereby permitting the exhaust to take place through the exhaust port 17 of the slide valve which by this time has risen to its extreme upper position. This point of exhausting varies with different engine 80 builders, and of course may be arranged to suit the ideas of the particular builder by shifting the eccentrics with relation to one another, but for the purposes of this description it may be assumed that, roughly speaking, the ignition occurs at the top of the piston stroke and the exhaust occurs at approximately the bottom. At the time the exhaust commences, it will be seen that the slide valve 15 will have risen to its extreme 85 upper stroke, completely lapping the intake port 11 and preventing any of the exhaust from entering the intake passages of the engine when the intake port 14 of cylinder 6 descends below its packing 19, which occurs 90 quickly after the exhaust stroke commences because, as will be seen, the eccentric of the cylinder 6 at this time is passing through the rapid portion of its orbit although the eccentric of the valve 15 is moving slowly 95 downward through the upper half of its orbit and thereby avoiding the opening of the intake port 11 through the port 16, the exhaust port 17 at this time, however, being fully in register with the casing exhaust 100 port 12 and tarrying in its movement to 105 permit the exhaust port 13 to catch up with it and come into full register therewith before it is lapped with the wall of the casing, which will occur when this exhaust port 17 reaches its intermediate position. In actual practice, of course, the point of exhaust will take place when the crank is some distance from its lowest position, as indicated in Diagram D, and the eccentric of the slide valve 110 15 will consequently be a little below its highest position, as indicated in said diagram, giving the valve an infinitesimal upward movement until the summit is 115 reached, but for the purposes of this description of the approximate operation of the parts it may be assumed that the dots along the slide valve and cylinder in these diagrams correspond with the highest, lowest, and intermediate positions of the eccen- 120 trics. From the positions of the parts shown in Fig. 7, the next half throw of the main crank or inward stroke of the piston, forcing the burned gases out through the 125 exhaust ports, brings the parts back again 130

into the position shown in Fig. 4, thereby completing the cycle, when the suction stroke again commences.

What I claim is:

5. 1. In an explosion engine the combination of a cylinder casing, a head projecting into said casing, a reciprocating cylinder having intake and exhaust ports telescoped with said head and coöperating therewith to control communication with the said cylinder, the wall of the casing being fixed against movement with said cylinder and the outer face of the cylinder being disposed immediately adjacent thereto and guided thereby, a slide valve movable longitudinally of said cylinder and coöperating with the casing to control communication with the cylinder through said exhaust port, a piston reciprocating in said cylinder with relation thereto, means connecting the piston with said cylinder and slide valve whereby the said intake port is uncovered during an outward piston stroke and is closed and maintained closed during the next three piston strokes, and the said exhaust port is opened at approximately the conclusion of the third one of the aforesaid piston strokes and is closed at the conclusion of the fourth one of said strokes.
30. 2. In an explosion engine the combination of a cylinder casing, a head projecting into said casing, a reciprocating cylinder telescoped with said head and coöperating therewith to control communication with the cylinder, a slide valve movable longitudinally of the cylinder and disposed with its inner face directly adjacent the outer face of the cylinder and coöperating on its outer face with the casing for controlling communication with said cylinder, a piston reciprocating in the cylinder with relation thereto, and means connecting the cylinder and slide valve with the piston for reciprocating them with relation to one another and to the piston.
35. 3. In an explosion engine the combination of a cylinder casing, a head projecting into said casing, a reciprocating cylinder telescoped with said head and coöperating therewith to control communication with the cylinder, the wall of the casing being fixed against movement with the cylinder and the outer face of the cylinder being immediately adjacent thereto and guided thereby, a slide valve movable longitudinally of the cylinder and coöperating with the casing to control communication with the cylinder, a piston reciprocating in said cylinder with relation thereto, a crank shaft connected with the piston, and means connecting the crank shaft with the said cylinder and slide valve for reciprocating them relatively to one another and to the said cylinder and piston.
40. 4. In an explosion engine the combination of a cylinder casing, a head projecting into said casing, a reciprocating cylinder telescoped with said head and coöperating therewith to control communication with the cylinder, the wall of the casing being fixed against movement with the cylinder and the outer face of the cylinder being disposed immediately adjacent thereto and guided thereby, a slide valve movable longitudinally of the cylinder and coöperating with the casing to control communication with the cylinder, a piston reciprocating in said cylinder with relation thereto, a crank shaft connected with the piston, and means connecting the crank shaft with the said cylinder and slide valve for reciprocating them relatively to one another and to the said cylinder and piston.
45. 5. In an explosion engine the combination of a cylinder casing, a head therein, a reciprocating cylinder telescoped on said head and coöperating therewith to control communication with the cylinder at one period, a slide valve coöperating with the casing for controlling communication with the cylinder at another period, the wall of the casing being exposed to direct contact by said cylinder and fixed against longitudinal movement therewith on one side, a piston reciprocating in the cylinder relatively thereto, a crank shaft operated by the piston, and means connecting the cylinder and slide valve with the piston for moving them relative to one another and to the head and piston.
50. 6. In an explosion engine the combination of a cylinder casing, a head therein fixed against axial movement, a reciprocating cylinder telescoped on said head and coöperating with the casing for controlling communication with the cylinder at one period, a slide valve arranged between said casing and cylinder for controlling communication with the cylinder at another period, the wall of said casing being exposed to direct contact by said cylinder and fixed against longitudinal movement therewith, a piston reciprocating in said cylinder relatively thereto, a crank shaft operated by the piston, and means connecting said cylinder and slide valve with the piston for moving them relatively to one another and to the head and piston.
55. 7. In an explosion engine the combination of a cylinder casing having a head fixed with relation thereto and projecting thereinto, a reciprocating cylinder having a port and telescoped on said head and coöperating therewith to control communication with the interior of said cylinder at one period, an arc-shaped element constituting a slide valve interposed between said casing and cylinder and coöperating with the casing for closing said port and thereby controlling communication with said cylinder at another period, a piston reciprocating in said cylinder relatively thereto, and means connecting the piston with said cylinder and slide valve for moving them relatively to the head and casing and to one another.
60. 8. In an explosion engine the combination of a cylinder casing having a port, a head projecting into said casing and fixed with relation thereto, a reciprocating cylinder telescoped with said head and coöperating therewith to close communication with the interior of said cylinder, a slide valve interposed between said casing and the side of said cylinder and coöperating with the casing for controlling said port therein, one side wall of said casing contiguous to said cylinder being fixed against movement and disposed immediately adjacent said cylinder to provide a fixed guide therefor, a piston recip-

- rocating in said cylinder relatively thereto, and means operatively connecting said cylinder and slide valve with the piston for moving them relatively to one another and to the casing and head.
8. In an explosion engine the combination of a fixed cylinder casing having a port, a head projecting into said casing and fixed with relation thereto, a reciprocating cylinder telescoped on said head and coöperating therewith to control communication with the interior of the cylinder, a slide valve disposed adjacent the wall of said cylinder and coöperating with said casing for controlling the port therein, the side wall of said casing contiguous to said cylinder being fixed against movement therewith to provide a fixed guide therefor, a piston reciprocating in said cylinder relatively thereto, means for firing a charge in said cylinder between and against the said head and piston, and means operatively connecting said cylinder and slide valve with the piston for moving them relatively to one another and to the casing and head.
9. In an explosion engine the combination of a fixed cylinder casing having internally spaced guide-ways parallel with its axis, a reciprocating cylinder inclosed by said casing and having a port, a slide valve interposed between said guide-ways and between the outer face of the cylinder and inner face of said casing and coöperating with the casing to control communication with said cylinder through said port, a head fixed against axial movement with said cylinder and telescoped therewith for controlling communication with the cylinder, a piston reciprocating in said cylinder relatively thereto, and means connecting said cylinder and slide valve with the piston for reciprocating them relatively to one another and to the piston.
10. In an explosion engine the combination of a fixed cylinder casing having internally spaced guideways parallel with its axis, a reciprocating cylinder inclosed by said casing, a slide valve interposed between said guideways and between the outer face of the cylinder and inner face of the casing and coöperating with the casing to control communication with the cylinder, a head fixed against axial movement with said cylinder and telescoped therewith also for controlling communication with the cylinder, a piston reciprocating in said cylinder relatively thereto, and means connecting said cylinder and valve with the piston for reciprocating them relatively to one another and to the piston.
11. In an explosion engine the combination of a fixed cylinder casing having internally spaced guideways parallel with its axis, a reciprocating cylinder inclosed in said casing, a slide valve interposed be-
- tween said guideways contiguous to the cylinder and casing and coöperating with the casing to control communication with the cylinder, a head fixed against axial movement with said cylinder and telescoped therewith for controlling communication with the cylinder, a piston reciprocating in said cylinder relatively thereto, and means connecting said cylinder and valve with the piston for reciprocating them relatively to one another and to the piston.
12. In an explosion engine the combination of a cylinder casing having its bore formed on different radii throughout different portions of its circumference in the same plane transverse to its axis, a reciprocating cylinder guided in said casing by the smaller portion of its circumference, a slide valve interposed between said cylinder and casing at the larger portion of the casing circumference and coöperating with the casing to control communication with the cylinder, a head closing one end of said cylinder and coöperating therewith to control communication with the cylinder, a piston closing the other end of the cylinder and reciprocating therein with relation thereto, and means connecting the cylinder and slide valve with the piston for reciprocating them relatively to one another and to the piston.
13. In an explosion engine the combination of a cylinder casing having its bore formed on different radii throughout different portions of its circumference in the same transverse plane, a reciprocating cylinder guided in said casing by the smaller portions of its circumference, an arc-shaped slide valve interposed between the said cylinder and casing at the larger portion of the casing circumference and coöperating with the casing to control communication with said cylinder, a head closing one end of said cylinder and coöperating therewith to control communication with the cylinder, a piston reciprocating in said cylinder with relation thereto, a crank shaft connected to the piston, and means connecting said cylinder and slide valve with the crank shaft for reciprocating them relatively to one another and to the piston, a number of strokes proportionate to the cycle of operation and less in number than the number of strokes of the piston belonging to the same cycle.
14. In an explosion engine the combination of a cylinder casing having its bore formed on different radii throughout different portions of its circumference in the same transverse plane, a reciprocating cylinder guided in said casing by the smaller portion of its circumference, a slide valve interposed between said cylinder and casing at the larger portion of the casing circumference and coöperating on its outer face directly with the inner face of the cas-

ing to control communication with said cylinder and having its inner face directly contiguous to said cylinder, a head closing one end of said cylinder and coöperating with the cylinder to control communication therewith, a piston reciprocating in the cylinder and opposed to said head and movable relatively thereto, and means connecting the cylinder and slide valve with the piston for reciprocating them relatively to one another and to the piston, said slide valve being in the form of an arc in cross section and the smaller portion of the circumference of said casing being formed by an arc-shaped separate filling fitted in said casing and being of the same radius as said slide valve and fixed against longitudinal movement therewith.

15. In an explosion engine the combination of a fixed cylinder casing, an arc-shaped filling fitted against one side of the wall of said casing and held from longitudinal movement therein, an arc-shaped slide valve fitted between the edges of the 20 arc-shaped filling, against the opposite side of the wall of the casing, a reciprocating cylinder fitted between said filling and slide valve and holding them against lateral displacement, a head fixed to said cylinder casing and telescoped with said reciprocating cylinder for controlling communication with the interior of the cylinder, said cylinder having a port, means for reciprocating said slide valve and cylinder 25 with relation to one another for controlling the said port, and a piston reciprocating in said cylinder with relation thereto and to said slide valve.

16. In an explosion engine the combination of a cylinder casing provided internally with a fixed cylinder guide, a reciprocating cylinder arranged within said casing and guide by said guide, a piston reciprocating in said cylinder with relation

thereto, a crank shaft, a piston rod connecting the piston with the crank shaft, the said cylinder guide being situated at the side of the casing to receive the lateral thrust of the piston and cylinder due to the angularity of the piston rod during the explosion stroke, a head telescoped with said cylinder, a slide valve operatively related to the casing, and means connecting the piston with said cylinder and slide valve for reciprocating them relatively to one another and to the piston, whereby they co-operate respectively with the head and casing for controlling communication with the cylinder.

17. In an explosion engine, the combination of a cylinder casing provided with an inner concentric groove about the base thereof, a cylindrical slit shell provided with a ridge to fit the groove and positioned therein, the shell fitting within the cylinder, a cylindrical arc-shaped slide fitting in the slit portion of the shell between the shoulders formed by said slit and formed with port openings, a cylindrical shell fitting inside of said slit shell and slide having port 60 openings, positively operated adjustable eccentric means to reciprocate the said inner shell and the slide with respect to each other and the cylinder casing, said cylinder casings having port openings which register with the openings in the cylindrical shell and in the slide at certain times to control communication with the cylinder, and a piston reciprocable in the cylinder within the said movable cylindrical shell, 65 the shell co-operating with the piston to relieve the slide valve from strain or pressure due to the lateral thrust of the piston during the working stroke.
